UNITED STATES PATENT OFFICE

107,242

DESIGN FOR A STORE

Howard Irvin Kuebler, Baltimore, Md., assignor
to Cannon Shoe Company, Baltimore, Md., a
corporation of Massachusetts

Application August 20, 1937, Serial No. 71,220

Term of patent 14 years

To all whom it may concern:

Be it known that I, Howard Irvin Kuebler, a citizen of the United States and resident of Baltimore, State of Maryland, whose post office address is 2666 Lauretta Avenue, Baltimore, Maryland, have invented a new, original, and ornamental Design for a Store, of which the following is a specification, reference being had to the accompanying drawing forming a part thereof.

Figure 1 is a front elevation of the front of the store, embodying my new design;

Figure 2 is a horizontal section of the new design taken above the plane of the floor; and

Figure 3 is an elevational view of the interior of the store taken from a point to the rear of the windows and looking toward the rear of the store, with parts in section.

The stippling shown in the drawing is to indicate the design of contrasting color but it is not hatched for any specific coloring.

I claim:

The ornamental design for a store, as shown and described.

HOWARD IRVIN KUEBLER.
